UNITED STATES PATENT OFFICE

105,339

DESIGN FOR A MUSICAL INSTRUMENT

Charles Mickus, Quincy, Mass.

Application March 6, 1937, Serial No. 68,046

Term of patent 7 years

To all whom it may concern:

Be it known that I, Charles Mickus, a citizen of the United States, residing at Quincy, in the county of Norfolk and Commonwealth of Massachusetts, have invented a certain new, original, and ornamental Design for a Musical Instrument, of which the following is a specification, reference being had to the accompanying drawing, forming a part thereof.

Fig. 1 is a top plan view of the article, showing my new design; and

Fig. 2 is a side elevational view thereof.

I claim:

The ornamental design for a musical instrument substantially as shown.

CHARLES MICKUS.
